UNITED STATES PATENT OFFICE

THOMAS C. McBRIDE, OF PHILADELPHIA, PENNSYLVANIA, ASSIGNOR TO WORTHINGTON PUMP AND MACHINERY CORPORATION, OF NEW YORK, N. Y., A CORPORATION OF VIRGINIA

FEED-WATER HEATER

Application filed June 4, 1926. Serial No. 113,620.

This invention relates to feed water heating apparatus and especially to feed water heaters of the open type wherein the water is heated by contact with steam, preferably the exhaust steam from an engine or the like, and it is an object of the present invention to provide a feed water heating apparatus which will overcome certain disadvantages of heaters of approved types in commercial use, and to provide a feed water heating apparatus, which, is compact, light in weight, and will occupy a small space for installation.

Also in certain types of commercially known heaters, various types of automatic apparatus, floats, etc., for controls, some being dependent upon the water level within the heater, are provided while the present invention comprehends the provision of a feed water heating apparatus in which the control requires no floats or other automatic apparatus, and one which, owing to the employment of a rotary or centrifugal hot water or boiler feed pump, will provide a steady flow in the discharge which will not interfere with the boiler check, in contradistinction with the intermittent flow as provided by displacement pumps.

Another object of the present invention is to provide a feed water heating apparatus particularly adaptable for use on locomotives and which is designed to facilitate the replacement or repair of parts with minimum effort and without disturbance of the connections between the heater and locomotive parts. The above is accomplished by the provision of a feed water heating apparatus in which the heating chamber and its closely related parts, in which replacement or repairs are seldom required, are formed in one casting or unit and attached to the locomotive at any convenient point, while the pumping mechanism is formed in a unit detachably connected, preferably at the bottom of the heating chamber unit and free from any direct connection with the locomotive, thereby permitting removal of the pumping unit for replacement or repair without affecting connections between the locomotive parts and the heating chamber unit.

Other features of the present invention

are; the provision of a return or excess water pump which returns the varying excess of water due to steam condensation to the heating chamber of the apparatus, discharging into the discharge of the cold water supply pump, and thereby regulating the capacity of the cold water supply pump and regulating the quantity of cold water supplied to the heating chamber, by the over-flow of excess water; a priming mechanism controlled by water in the heating apparatus for priming the rotary or centrifugal pump which supplies the cold water to the heating chamber, said priming mechanism also controlling the delivery of operating steam to the engine employed for operating the pumps, whereby in starting, dry running of the rotary or centrifugal pumps is prevented and their operation is automatically set up when sufficient water is in the heating apparatus to fill the pumps; and the provision of suitable passageways and means for directing the exhaust steam from the pump operating engine or turbine into the heating chamber of the feed water heating apparatus.

With these objects in view, the invention consists in various features of construction and combination of parts, which will be first described in connection with the accompanying drawings, showing a feed water heater of the preferred form embodying the invention, and the features forming the invention will be specifically pointed out in the claims.

In the drawings—

Figure 1 is a vertical section through the improved feed water heater.

Figure 2 is a fragmentary side elevation of the feed water heater taken on the line 2—2 of Figure 1.

Figure 3 is a fragmentary vertical section taken on the line 3—3 of Figure 1.

Figure 4 is a horizontal section through the heater on the line 4—4 of Figure 1.

Figure 5 is a horizontal section through the heater on the line 5—5 of Figure 1.

Figure 6 is a horizontal section on the line 6—6 of Figure 1.

Figure 7 is a fragmentary vertical section on the line 7—7 of Figure 1.

Figure 8 is a fragmentary vertical section through the feed water heater.

Figure 9 is a fragmentary section through a modified form of the heater.

5 Referring more particularly to the drawings, the improved feed water heater comprises the main or heating chamber 1 to which the cold water is delivered by a spray valve 2 of any approved construction, and the cold 10 water is heated in the chamber 1 by contact with exhaust steam from locomotive cylinders or other suitable source which enters the chamber 1 through the inlet 3.

The supply of cold water is from the tender 15 (not shown) when the heater is used on a locomotive, and otherwise from any suitable source, through the pipe 4 to a rotary pump 5. The cold water enters the suction 6 of the pump 5 and is forced by the impeller 7 20 upwardly through the pipe 8 into the priming chamber 9 from which it passes through the passage 10 into the chamber 11 and thence through the spray valve 2 into the heating chamber 1.

25 The pump impeller 7 is mounted upon the shaft 12 of the pumping unit 13 which shaft is driven by a turbine 14 mounted thereon. Live steam, from any suitable source is provided for operating the turbine 14 and this 30 steam is delivered through a pipe 15 to a valve chamber 16 (see Figs. 1 and 4). The valve cone 17 in the valve chamber 16 is operated through a series of links 18 by a float 19 which is positioned in the priming chamber 9 so 35 that the delivery of operating steam to the turbine 14 will be controlled by the quantity of water or the water level in the priming chamber 9, and when the heater is in water-heating and boiler-feeding operation the 40 steam passes through the valve chamber 16, pipe 20, into the chamber 21 from which it passes into the turbine structure 14 for rotating the runner thereof, to operate the shaft 12 and the pumps mounted thereon.

45 In starting the heating apparatus or at such times when the water in the heater is below a pre-determined level, the lowered position of the float 19 will position the valve 17 to prevent flow of steam to 50 the turbine 14 and open the valve 16a to permit a quantity of steam to pass through the by-pass pipe 23 for operating the ejector or jet pump 24. The suction of the jet pump 24 is connected to the water supply pipe 4 55 on one side of a check valve 25 while its discharge is into the pipe 4 on the opposite side of the check valve, and through the cold water supply pump 5 and pipe 8 into the heating apparatus. When the operation of 60 the jet pump 24 has supplied sufficient water to prime the supply pump and to raise the float 19, the raising of the float will operate the valve 17 to cut off the supply of steam to the jet pump and open the passageway of 65 operating steam to the turbine 14, thus auto-

matically setting up operation of the turbine and pumps.

The hot water, that is, the water which is heated in the chamber 1 by its contact with the exhaust steam entering the heating chamber 1 into the chamber 27, which is an extension of the chamber 1, and passes from the chamber 27 into the suction 28 of the first stage of a multiple stage rotary boiler feed pump 29. The hot water passes from the discharge of the first stage of the pump 29 through the passageway 30 into the suction of the second or successive stage of the pump 29, being discharged from the final stage of the pump 29 through the suitable discharge passageway 31 to the boiler or other utilizing apparatus. 70 75 80

To prevent flooding of the heater by the varying excess of water due to steam condensation in the heater, an over-flow pipe 32 is provided which rises centrally within the chamber 1 and the height of which controls the water level in the heater, any excess water in the heater flows into the over-flow pipe 32 and passes downwardly into the chamber 33 of the pumping unit 13. The excess or over-flow is taken from the chamber 33 by the return pump 34 which delivers it into the discharge of the cold water supply pump 5, returning it, with the cold water discharged 90 95 by the pump 5, to the heater.

The cold water supply pump 5 being a centrifugal pump, the amount of water it delivers is largely controlled by the pressure against which it must deliver and the return pump 34 is designed to generate a discharge pressure sufficiently high to oppose the discharge pressure of the supply pump 5 and consequently reduce or regulate the amount of water discharged by the pump 5. Thus, 100 when there is an over-flow of excess water from the chamber 1 through the over-flow pipe 32 and return pump 34, the amount of cold water delivered to the chamber 1 will be in inverse proportion to the quantity of 105 excess water returned to the chamber 1 through the discharge of the pumps 34 and 5, and when there is no excess water over-flowing from the chamber 1 the pump 5 will operate at full capacity and compensate for the 110 lack of excess water in the heating chamber. 115

In the drawings, the return pump 34 is shown as comprising vanes on the back of the impeller 7 of the pump 5, and the chamber 33 is illustrated as having communication with the chamber of the pump 5 through a suitable opening 36. Thus it will be seen that a single impeller or rotary pump 13 provided with multiple inlets or suctions and a single discharge permits the return of the excess water from the chamber 1 through the heater, and consequently, eliminates the loss of any heat which this water might contain. 120 125

While in the drawings the return of excess water pump 34 is shown as vanes on the 130

back of the impeller 7 of the pump 5, it is to be understood that the return pump 34 may be separate and independent of the pump 5, if desired without departing from the 5 spirit of this invention although it is desirable to have its discharge common with that of the pump 5.

If it is so desired, a check valve 37 of any approved construction may be mounted in the 10 delivery or discharge pipe 8 of the cold water supply pump so as to prevent water being forced backwards through the cold water supply pump when the locomotive drivers slip or under other circumstances which might 15 arise, and a check valve 37' is positioned in the connection between the heating chamber 1 and the suction of the return or excess water pump 34, thus water will be prevented from flowing by gravity from high tenders or other 20 high water supply sources, through the heater, which may be positioned at a low elevation, when the pumping unit is not operating.

It is desirable to utilize the heat from the 25 turbine exhaust by delivering the said exhaust into the exhaust steam inlet 3, through the opening 60 as shown in the modified form illustrated in Figure 9, where it will mingle with the exhaust steam entering the heating 30 chamber 1. However; in the preferred form shown in the drawings, the exhaust steam from the turbine 14 is shown passing from the casing of the turbine through a suitable outlet or exhaust opening 38 into a chamber 39. The exhaust steam from the turbine 35 passes through a suitable check valve 40' from the chamber 39 into the chamber 40 from which it passes through the passageway 41 into the casing 42 of a jet condenser 40 construction 43. A by-pass 44 is provided in the heater structure which has inlet communication with the priming chamber 9 so that a part of the cold water delivered to the feed water heater by the pump 5 will be diverted through the passageway 44, to the 45 passageway 44' and be directed by the nozzle 45 through the tube 46 of the jet condenser 43. The tube 46 is perforated as shown at 47 so as to permit the exhaust steam from the turbine to be taken up by the water passing 50 through the tube and condensed and any condensate which settles in the bottom of the condenser or chamber 42 of the jet condenser 43 will be drawn into the open, flared bottom of the tube 46, and will pass through the tube with the water and from the jet condenser structure 43 into the chamber 11 where it mingles with the cold water supplied to the chamber 11 from the priming chamber 9 55 through the passageway 10, and will be delivered through a spray valve 2 into the heating chamber 1.

An air vent 49 is provided which has communication with the chamber 50 formed at 60 the top of the chamber 1 so as to permit the

escape of any accumulation of air within the heater and a suitable cone or hood 51 is mounted over the top of the over-flow pipe 32 so as to prevent the cold water or condensed exhaust steam from entering the over-flow pipe 32 from above. Movement of the check valve 40' is limited by a suitable stop lever 52 which projects into the chamber 40 in the path of movement of the check valve 40'. A safety valve 53 is carried by the 70 casing of the feed water heater and has communication with the exhaust steam inlet 3.

The feed water heating apparatus herein described is particularly adaptable for use on locomotives, and for purposes of attachment to a locomotive suitable attaching brackets 60' are formed on the casting forming the heating chamber and its companion passageway and parts, while the pumping unit 13, which is attached to the lower end of the heating chamber carrying casting (the line of separation of the units being clearly shown at A in Figure 1 of the drawings) is free from any attachment to the locomotive. This construction permits all of the 80 attaching bolts to be in one casting, and accurately spaced, and permits detachment of the pumping unit 13 containing the more intricate parts of the feed water heating apparatus, for replacement, repair or for any 85 other purpose, without affecting the attachment of the apparatus to the locomotives and without disturbing connections between the locomotive parts and the heating chamber unit.

The mounting of the various pumps 5, 29 and 34 and the turbine 14 on a single horizontal shaft 12 also facilitates the above advantages and permits the utilizing of smaller space for the heater as well as permitting the 90 turbine and pumps which must have greater dimension than the heating chamber, to be located well down and fit under the curve of a locomotive boiler when the feed water heating apparatus is attached to the side of the boiler.

The operation of the improved feed water heater will be apparent from the foregoing description taken in connection with the accompanying drawings. However, briefly summarizing, the operation is as follows:

The cold or supply water is drawn from a suitable supply source such as a tender of the locomotive (not shown) by the rotary cold water pump 5 and it is delivered through the discharge 8 into the priming chamber 9 of the heater. From the priming chamber 9 the cold water is delivered through the passageway 10 to the spray valve 2 and passes through the spray valve in a sprayed manner into the chamber 1 where it engages with the exhaust steam from the locomotive cylinders entering the chamber through the exhaust steam inlet 3. The contact of the cold water with the steam will heat the water and

condense the steam and the resulting hot water and condensate will pass downwardly into the lower part 27 of the chamber 1 and be drawn therefrom into the initial stage of 5 the multi-stage rotary pump 29. After passing through the various stages of the pump 29 it is delivered from the discharge 31 of the pump to the boiler to supply the necessary water to the boiler at a relatively high temperature. The ejector or jet pump 24 which is brought into operation by the low water level in the control chamber 9 will draw water from the cold water supply source sufficiently to prime the pump 5 and operate the float 10 19 which will operate the valve 17 to deliver the line or operating steam to the turbine 14. The excess or over-flow water from the chamber 1 will be returned thereto by the return pump 34 through the discharge of the 15 20 supply pump 5.

From the foregoing description taken in connection with the accompanying drawings, it will be apparent that a compact, efficient and relatively simple feed water heater embodying rotary or centrifugal turbine-operated pumps has been provided which will effectively heat the feed water and deliver it to the boiler with a minimum loss of heat and of power. By placing the pumping unit 25 30 which comprises the supply pump, excess water return pump, the boiler feed pump and turbine on a single shaft, the weight and size of the feed water heater will be materially reduced over types of similar heaters now in use and the heater will occupy a 35 relatively small amount of space when installed.

It will be understood that the invention is not to be limited to the specific construction or arrangement of parts shown but that these may be modified widely within the invention defined by the claims.

What is claimed is:

1. In a feed water heating apparatus, a 45 heating chamber, a pump for delivering water to said chamber, a steam inlet for said chamber to permit contact of steam and water in the chamber, a pump for removing excess water from said chamber and having its discharge into the discharge of said delivery pump, a pump for delivering heated water from said chamber, and means for operating said pumps.

2. In a feed water heating apparatus, a 55 heating chamber, a steam inlet for said chamber to permit contact of steam and water in the chamber, a pumping unit including a pump for delivering water to said chamber, a pump for delivering heated water from 60 said chamber, an excess water pump for taking excess water from said chamber and returning it thereto, and means for operating said pumps.

3. In a feed water heating apparatus, a 65 heating chamber, a rotary pump for supply-

ing cold water to said chamber, a rotary pump for delivering heated water from said chamber, and a turbine for driving said pumps, said pumps and turbine mounted upon a single shaft.

4. In a feed water heater, a heating chamber, a pump for supplying water to said chamber, a pump for delivering heated water from said chamber, and priming means controlled by water in the heating apparatus for 70 priming said supply pump.

5. In a feed water heater, a heating chamber, a pump for supplying water to said chamber, a pump for delivering heated water from said chamber, a turbine for driving said pumps, priming means for priming said supply, and means controlled by water in the heating apparatus for controlling said priming means and controlling the delivery of operating steam to said turbine.

6. In a feed water heating apparatus, a heating chamber, a pump for supplying water to said chamber, a pump for delivering heated water from said chamber, a turbine for driving said pumps, a jet pump for priming said supply pump and means controlled by water in the heating apparatus for controlling operation of said jet pump.

7. In a feed water heating apparatus, a heating chamber, a pump for supplying water to said chamber, a pump for delivering heated water from said chamber, a turbine for driving said pumps, a jet pump for priming said supply pump and means controlled by water in the heating apparatus for controlling operation of said jet pump, said means also controlling delivery of operating steam to said turbine.

8. In a feed water heating apparatus, a housing, a heating chamber therein, a pump for supplying water to said chamber, a pump for delivering heated water from said chamber, a turbine for driving said pumps, said housing provided with passageways to lead the exhaust steam from said turbine into said heating chamber.

9. In a feed water heating apparatus, a housing, a heating chamber therein, a pump for supplying water to said chamber, a pump for delivering heated water from said chamber, a turbine for driving said pumps, said housing provided with passageways to lead the exhaust steam from said turbine into said heating chamber, said pumps and turbine combined in a unit and mounted upon a single shaft.

10. In a feed water heating apparatus, a heating chamber, a pump for supplying water to said chamber, a pump for delivering heated water from said chamber, a turbine for driving said pumps, said heating apparatus provided with passageways to lead the exhaust steam from said turbine into said heating chamber, said pumps and turbines combined in a unit mounted upon a single 120 125 130

- shaft, and a rotary pump for taking excess water from said heating chamber and returning it to the inlet of the heating chamber.
11. In a feed water heating apparatus, a housing, a heating chamber having a steam inlet to permit contact of steam and water in the chamber, a pump for delivering water to said chamber, a pump for delivering heated water from said chamber, a turbine for operating said pumps, said heating apparatus provided with passageways to lead the exhaust steam from said turbine into said heating chamber. 70
12. In a feed water heating apparatus, a heating chamber, a pump for supplying water to said chamber, an excess water pump for taking excess water from said chamber, said supply pump and excess water pump having a common discharge. 80
13. In a feed water heating apparatus, a heating chamber, a rotary pump for supplying water to said chamber, an excess water pump for taking excess water from said chamber, said supply pump and excess water pump having a common discharge, a turbine for operating said pumps, said heating apparatus provided with passageways for delivering exhaust steam from said turbine to said heating chamber. 85
14. In a feed water heating apparatus, a heating chamber, a rotary pump for supplying water to said chamber, an excess water pump for taking excess water from said chamber, said supply pump and excess water pump having a common discharge, a turbine for operating said pumps, said heating apparatus provided with passageways for delivering exhaust steam from said turbine to said heating chamber, and a priming means controlled by water in the heating apparatus for priming said supply pump. 90
15. In a feed water heating apparatus, a heating chamber, a rotary pump for supplying water to said chamber, an excess water pump for taking excess water from said chamber, said supply pump and excess water pump having a common discharge, and a check valve in the discharge of said pumps to prevent backflow of water from the heating apparatus into the pumps. 100
16. In a feed water heating apparatus, a heating chamber, a rotary pump for supplying water to said chamber, an excess water pump for taking excess water from said chamber, said supply pump and excess water pump having a common discharge, a check valve in the discharge of said pumps to prevent backflow of water from the heating apparatus into the pumps, and a check valve in the connection between said excess water pump and heating chamber to prevent reverse flow of water into the heating chamber. 110
17. In a feed water heating apparatus, a heating chamber, a rotary pump for supplying water to said chamber, an excess water pump for taking excess water from said chamber, said supply pump and excess water pump having a common discharge, and a check valve in the delivery from the heating chamber to the excess water pump to prevent reverse flow of water into the heater. 120
18. In a feed water heating apparatus, a heating chamber, a rotary pump for supplying water to said chamber, an excess water pump for taking excess water from said chamber, said supply pump and excess water pump having a common discharge, and priming means controlled by the water in the heating apparatus for priming said supply pump. 125
19. In a feed water heating apparatus, a heating chamber, a rotary pump for supplying water to said chamber, an excess water pump for taking excess water from said chamber, said supply pump and excess water pump having a common discharge, a turbine for operating said pumps, and means controlled by the water in the heating apparatus for controlling the delivery of operating steam to said turbine. 130
20. In a feed water heating apparatus, a housing, a heating chamber therein and having a steam inlet, means for delivering water to said chamber for contact with said steam, and a rotary pump for delivering hot water from said chamber, a turbine for driving said rotary pump, said heating apparatus having passageways for delivering exhaust steam from said turbine to said heating chamber. 95
21. In a feed water heating apparatus, a heating chamber having a steam inlet, a spray valve for delivering water in sprays into said heating chamber for contact with the steam, a rotary pump for delivering hot water from said chamber and means controlled by the water in the heating apparatus for controlling operation of said pump. 105
22. In a feed water heating apparatus, a heating chamber, a pumping unit, an engine for operating said pumping unit and a condenser for condensing the exhaust steam from said engine, said condenser delivering the condensate into said heating chamber. 110
23. In a feed water heating apparatus, a heating chamber, a pumping unit, an engine for operating said pumping unit, a jet condenser, means for delivering a part of the supply water from the pumping unit to said condenser, said condenser receiving the exhaust steam from said engine and having its discharge to said heating chamber, whereby the mingled supply water and condensate will be delivered to said heating chamber. 115
24. In a heating apparatus, a heating chamber, a cold water supply pump, an operating engine therefor, a condenser receiving exhaust steam from said engine, said heating apparatus provided with a by-pass for diverting a part of the supply water to said condenser. 120
25. In a heating apparatus, a heating

- chamber, a cold water supply pump, a turbine for operating said supply pump, a condenser receiving exhaust from said turbine, said heating apparatus provided with a by-pass 6 for diverting a part of the supply water to said condenser, said condenser having its discharge to said heating chamber.
26. In a heating apparatus, a heating chamber, a cold water supply pump, a turbine 10 for operating said supply pump, a condenser receiving exhaust from said turbine, said heating apparatus provided with a by-pass for diverting a part of the supply water to said condenser, said condenser having its discharge 15 to said heating chamber, and a rotary pump for delivering heated water from said heating chamber.
27. In a heating apparatus, a heating chamber, a cold water supply pump, a turbine 20 for operating said supply pump, a condenser receiving exhaust from said turbine, said heating apparatus provided with a by-pass for diverting a part of the supply water to said condenser, said condenser having its discharge 25 to said heating chamber, and means controlled by water in the heating apparatus for controlling the supply of operating steam to said turbine.
28. In a heating apparatus, a heating chamber, a cold water supply pump, a turbine 30 for operating said supply pump, a condenser receiving exhaust from said turbine, said heating apparatus provided with a by-pass for diverting a part of the supply water to said condenser, said condenser having its discharge 35 to said heating chamber, and priming means controlled by water in the heating apparatus for priming said cold water supply pump.
- 40 29. In a feed water heating apparatus, a heating chamber, a cold water supply pump, a turbine for operating said pump, a condenser receiving exhaust steam from said turbine, said heating apparatus provided 45 with a by-pass for diverting a part of the supply water to said condenser, said condenser having its discharge to said heating chamber, a jet pump and means controlled by water in the heating apparatus for controlling the operation of said jet pump to prime said supply pump, said means cutting off the delivery of steam to said jet pump and permitting delivery of operating steam to said turbine upon the delivery of a pre- 50 determined quantity of water into the heating apparatus.
30. In a feed water heating apparatus, a cold water supply pump, a jet pump for priming said cold water supply pump, an engine for operating said pump and means controlled by water in the heating apparatus for permitting operation of said jet pump and for cutting off operation of the jet pump and permitting passage of operating steam 60 to the engine upon the delivery of a pre- 65 determined quantity of water to the heating apparatus.
31. In a feed water heating apparatus, a cold water supply pump, a jet pump, an engine for operating said pump for priming said cold water supply pump and means controlled by water in the heating apparatus for permitting operation of said jet pump and for cutting off operation of the jet pump and permitting passage of operating steam to the engine upon the delivery of a pre-determined quantity of water to the heating apparatus, and a rotary pump for delivering heated water from said heated chamber. 70 75
32. In a feed water heating apparatus, a heating chamber, a centrifugal pump for supplying cold water to the chamber, a return pump for taking excess water from the heating chamber, said return pump discharging into the discharge of said cold water supplying pump whereby the discharging capacity of said cold water supply pump will be regulated by the quantity of excess water pumped from the heating chamber. 80 85 90
33. In a feed water heating apparatus, a casting containing a heating chamber, attaching brackets on said casting to permit its attachment to a support, a second casting detachably connected to the bottom of said first casting and supported wholly by said first casting, a shaft carried by said second casting, a plurality of pumps mounted upon said shaft and a prime mover for operating said pumps mounted on said shaft. 95 100
34. In a feed water heating apparatus, a casting containing a heating chamber, attaching brackets on said casting to permit its attachment to a support, a second casting detachably connected to the bottom of said first casting and supported wholly by said first casting, a shaft carried by said second casting, a cold water supply pump mounted on said shaft, a return pump for drawing off excess water from the heating chamber and returning it thereto mounted on said shaft, a hot water discharge pump mounted on said shaft, and a turbine for operating said pumps mounted on said shaft. 105 110 115
35. In a feed water heating apparatus, a heating chamber, a pump for supplying water to said chamber, a jet pump for priming said supply pump, and means controlled by water in the heating apparatus for controlling operation of said jet pump. 120
36. In a feed water heater, a heating chamber, a pump for supplying water to said chamber, and priming means controlled by water in the heating apparatus for priming said supply pump. 125
37. In a feed water heating apparatus, a housing, a heating chamber therein, a pump for supplying water to said chamber, a turbine for driving said pump, said housing provided with passage ways to lead the exhaust steam 130

- from said turbine into said heating chamber.
38. In a feed water heating apparatus, a housing, a heating chamber therein, a centrifugal pump for supplying water to said chamber, a hot water pump for withdrawing hot water from said chamber, steam actuated means for operating said hot water pump, said housing provided with passage ways to lead exhaust steam from said steam actuated means into said heating chamber. 75
39. In a feed water heating apparatus, a heating chamber, a pump for delivering water to said chamber, said chamber having an inlet for steam, means for removing excess water from said chamber, said means connected to the discharge of said pump for delivering the excess water into the pump discharge for return to the chamber. 80
40. In a feed water heating apparatus, a heating chamber, a pump for delivering water to said chamber, said chamber having an inlet for steam, means for removing excess water from said chamber, said means connected to the discharge of said pump for delivering the excess water into the pump discharge for return to the chamber, and a check valve in the discharge of said pump to prevent back flow of water into the pump. 85
41. In a feed water heating apparatus, a heating chamber, a centrifugal pump for supplying water to said chamber, said chamber having an inlet for steam, means for removing excess water from said chamber, said means connected to the discharge of said centrifugal pump for delivering the excess water into the pump discharge for return to the chamber, a turbine for operating said pump, and means controlled by the water in the heating apparatus for controlling the delivery of operating steam to said turbine. 90
42. In a feed water heating apparatus, a heating chamber having a steam inlet, a spray valve for delivering water in sprays into said heating chamber for contact with the steam, a centrifugal pump for delivering water to said spray valve, a turbine for operating said pump, and means controlled by the water in the heating apparatus for controlling the delivery of operating steam to said turbine. 95
43. In a feed water heating apparatus, a heating chamber, means for spraying water into the heating chamber, a pump for delivering water to said spraying means, and means whereby water above a predetermined quantity in said heating chamber will proportionately reduce the discharge of said pump. 100
44. In a feed water heating apparatus, a heating chamber, means for spraying water into the heating chamber, a pump for delivering water to said spraying means, and means for delivering excess water above a predetermined quantity in said heating 105
- 110
- 115
- 120
- 125
